UNITED STATES PATENT OFFICE.

BRODIE J. RICHARDSON AND CLAIRE S. BARBER, OF WATERBURY, CONNECTICUT.

LOCKABLE HANDBAG-LATCH.

1,357,725.

Specification of Letters Patent.

Patented Nov. 2, 1920.

Application filed December 15, 1919. Serial No. 345,067.

To all whom it may concern:

Be it known that we, BRODIE J. RICHARDSON and CLAIRE S. BARBER, citizens of the United States, and residents, respectively, of 5 Waterbury, in the county of New Haven and State of Connecticut, have invented certain new and useful Improvements in Lockable Handbag-Latches, which improvements are fully set forth in the following specification.

10 This invention relates to improvements in devices of that class commonly mounted on one frame-section of a hand-bag, valise, suitcase, or the like, for coöperation, for fastening purposes and generally after the manner of a snap-latch, with a suitable tenoned hasp mounted on the opposed frame-section of such hand-bag, valise, suitcase, or the like, such devices embodying each a spring-controlled bolt lockable against retraction through the medium of a key-operable tumbler and being well-designed lockable hand-bag latches.

15 The object of this invention is to provide a hand-bag latch of the character above indicated, which shall be simple and comparatively inexpensive as regards its construction; durable, efficient and reliable in practical service; convenient in its application 20 to practical purposes; and which shall possess certain well-defined advantages over prior analogous constructions.

25 The invention consists in certain combinations, details and parts whereby, together with the novel disposition and relative arrangement of said parts, the attainment of the foregoing object is rendered practicable, all of which will be hereinafter more specifically referred to and set forth in the claims 30 hereto appended.

35 The invention is clearly illustrated in the accompanying drawings, wherein:

40 Figure 1 is a view in perspective of a hand-bag latch embodying our said improvements, opposed fragments of the frame-sections of a hand-bag, or like receptacle, being shown conjunctively therewith to better illustrate its practical application.

45 Fig. 2 is a top plan view of the latch, 50 detached.

55 Fig. 3 is a rear elevation of same, de-

tached, a portion of the wall of the hollow thumb-piece being broken away.

Fig. 4 is a view similar to Fig. 2, the top plate and the thumb-piece of the device being removed, and a fragment of the front wall of the casing being broken away. 55

Fig. 5 is an end elevation of the device, the near end wall and portion of the front wall of the casing being broken away. 60

Fig. 6 is a detail view partly in elevation and partly in section showing the application of a key to the key-receiving stem of our improved latch. 65

Having reference to the accompanying drawing, wherein similar reference-numerals denote like parts throughout the several views, we, in carrying out our present invention, provide a casing, preferably formed from a unitary blank of metal in sheet-form, 70 and consisting of a base 7, top-plate 7' and opposite end-pieces 7", 7"". 8 denotes a post rising from the base 7, midway the length thereof, and which freely pierces, primarily an evener 8' and thereafter an 75 operating bolt 8", the post 8 having a relatively enlarged, interior base 8''' between which and the evener aforesaid is interposed a controlling spring 9, preferably 80 spiral in form and encircling the post 8, as 85 shown.

The post 8 further freely pierces the tumbler-hub 9', positioned intermediate the medial section of the bolt 8" and the evener 8', and through the medium of which tumbler-hub, conjunctively with said evener, the distending tendency of the spring 9 is transmitted to said bolt to elastically hold the same at all times duly protracted, the tumbler-hub 9', together with the tumbler 9" 90 carried thereby, and the key-receiving stem 9''', rising from said tumbler-hub and fitted with a suitable key-way 10, being, accordingly, rotatable, all as a unit, on and relatively to said post. 95

Under the normal tendency of spring 9, transmitted as above stated, the medial section of the bolt 8" lies in contact with the top-plate 7, at the inner face or underside thereof; and, more specifically, said medial 100 section of the bolt 8" is merged into a down-turned segment 10', which, in turn, is

merged into a depressed, horizontal segment 10", which, in turn, is merged into a forwardly projecting terminal 10" fitted with an upstanding catch 11, the latter having a vertical rear edge and an advance edge curved upwardly and rearwardly, substantially as shown, and said segments and catch-affording terminal being, respectively, correspondingly formed and duplicated at the 10 opposite end of the medial section of the bolt 8", when deemed needful or desirable.

The front wall of the casing aforesaid has struck therefrom a fragment 11', which projects into the path of, and limits, the 15 downward movement, as against spring 9, of the bolt 8", and hence constitutes a stop for the latter, said stop being, when desired, employed in duplicate at opposite sides of the post 8, substantially as shown.

20 Said front wall of the casing aforesaid further has a fragment thereof drawn intact forwardly therefrom, for the formation of a horizontal, segmental socket 11", whose function will be made apparent hereinafter; 25 and further is provided with a suitable opening 11"" by way of which the tenon, as 12, of a suitable hasp, as 12', may be projected into the interior of the casing aforesaid, and which operation necessitates the 30 engagement by said tenon of the upwardly and rearwardly curved edge of the catch, as 11, provided for co-operation therewith, with the result that said catch is momentarily depressed and, under continued movement 35 inwardly of the tenon, permitted to snap back into a locking engagement with said tenon, which locking engagement may again be broken, as through depression of the bolt 8" fitted with said catch, all as in common 40 practice, and as will be readily understood, the opening 11"" being employed in duplicate when deemed needful or desirable, and as indicated in the drawing.

45 Depression of the bolt 8" is facilitated through the medium of a hollow thumb-piece 12", firmly mounted on the bolt 8", provided with a key-hole 12"" at its crown, and upwardly into which thumb-piece projects the fixed post 8, whereon is disposed to 50 horizontally rotate, intermediate the medial section of the bolt 8" and the evener 8', the tumbler 9", whose hub 9' serves to duly space apart said medial section of the bolt 8" and said evener, said tumbler-hub having 55 a diametrically reduced extension rising therefrom and which projects upwardly freely through the said medial section of the bolt 8", and is merged upwardly into the key-receiving stem 9'", having formed in 60 its top the key-way 10 hereinbefore alluded to, the post 8, accordingly, projecting upwardly through said tumbler-hub, the reduced extension thereof, and upwardly through and suitably beyond said key-receiving stem.

The tumbler 9" is at all times positioned in horizontal registry with the socket 11", and the plane of rotative movement thereof intersects the interior of said socket. Hence, when said tumbler shall have been so rotated 70 at any time on the post 8, say to the position indicated in full lines in Fig. 4, as to cause a marginal segment thereof to enter and occupy the socket 11", the bolt 8" will thereby be securely held against retraction, 75 while retraction of said bolt will be permitted whenever the tumbler 9" shall have been so rotated, at any time on the post 8, say to the position indicated in dotted lines in Fig. 4, as to withdraw from the socket 80 11" the entire marginal portion of said tumbler.

The operation of rotating the tumbler 9", in the one instance for locking the bolt 8" against retraction and in the other instance 85 for liberating said bolt for retraction, is facilitated through the medium of a suitable key, as 13, insertible endwise into the thumb-piece 12" by way of its key-hole 12""", having an axial recess 13' at its advance end-portion for the reception of the upper end-portion of the post 8, whereby said key is guided when manipulated for actuating the stem 9"" and therewith the tumbler 9", and having a suitable lug, as 13", for engagement with said stem by way of its key-way 95 10 formed therein.

The evener 8' serves both as a yielding retarder for the tumbler 9", when rotated, or under rotative action, and as a medium 100 whereby the bolt 8" is essentially constrained to move more evenly upwardly and downwardly along the post 8, the depending portion of said bolt being thereby serviceably held against any undue swinging action, as on a center of movement defined by the medial, horizontal section thereof.

To the foregoing ends the evener 8' has an end-detent 13""", which at all times occupies an open recess 14 with which the downturned segment 10', of the operating bolt is provided, said recess being ample to afford measurable clearance immediately beneath said detent to permit a measurable, downward tilting action on the part of said evener, together with the detent carried thereby, against the tendency of the spring 9, and independently of the bolt 8; which action on the part of said evener takes place whenever the tumbler 9" shall be duly rotated on the post 8, and by reason of the same engaging, depressing and overriding the small boss 14', whose yielding opposition to being so depressed insures the retardatory effect hereinbefore alluded to on said tumbler by the evener aforesaid, the latter affording said boss.

When deemed advisable the evener 8' may be provided with a suitable stop, as 14', which projects into the plane of movement 130

of the tumbler 9" and serves to limit the extent of rotative action thereof in either direction on the post 8.

The operation of our improved hand-bag 5 latch should be apparent from the foregoing description thereof; and in practice the same is mounted on one frame-section of a hand-bag, or the like, with its top-plate underlying snugly the top-member of such 10 frame-section, while a suitable, tenoned hasp, as 12', for coöperation therewith, is duly mounted on the opposite frame-section of such hand-bag, or the like, all as in common practice, save that when the top-member 15 of the frame-section to which our improved latch may be applied, is covered or faced with leather or the like, no objectionable protruding element, as a screw-head, is visible.

20 It will be seen that our improved latch is well adapted for the purposes for which it is intended, and further that the same may be modified, particularly as to the form of the various parts thereof and the details 25 of the general construction, without materially departing from the spirit and principle of our invention.

We claim:

1. A latch comprising a casing having an 30 upstanding post fixed therein; a bolt engageable with the tenon of a hasp and freely pierced by said post; an evener coöperating with said bolt in spaced relation thereto, and a bolt-controlling, resilient element, 35 the latter duly positioned within said casing and serving, indirectly through the medium of said evener, to yieldingly hold said bolt protracted.

2. A latch comprising a casing having an 40 upstanding post fixed therein; a bolt engageable with the tenon of a hasp, freely pierced by said post, and fitted with a suitable recess; an evener coöperating with said bolt in spaced relation thereto, and fitted with a 45 detent lying freely within the recess thereof; and a bolt-controlling, resilient element, the latter duly positioned within said casing and serving, indirectly through the medium of said evener, to yieldingly hold said bolt protracted.

3. A latch comprising a casing having an 50 upstanding post fixed therein; a bolt embodying a medial section merged into a downturned segment fitted with a recess, freely pierced at its medial section by said post, and engageable with the tenon of a hasp; an evener coöperating with said bolt in spaced relation thereto and serviceably projecting into and freely occupying the 55 recess thereof; and a bolt-controlling resilient element, the latter serving, indirectly through the medium of said evener, to yieldingly hold said bolt protracted.

4. A latch comprising a casing having an 60 upstanding post fixed therein; a bolt en-

gageable with the tenon of a hasp and freely pierced by said post; a non-yielding spacing medium, also pierced by said post beneath said bolt; and a bolt-controlling resilient element, the latter serving, coöperatively 70 with the spacing medium aforesaid, to yieldingly hold said bolt protracted.

5. A latch comprising a casing having an upstanding post fixed therein; a bolt engageable with the tenon of a hasp and 75 freely pierced by said post; an evener coöperating with said bolt; a spacing medium, also pierced by said post and serving to space said evener away from said bolt; and a bolt-controlling resilient element, the 80 latter serving, indirectly through the agency of said evener and said spacing medium, to yieldingly hold said bolt protracted.

6. A latch comprising a casing having an upstanding post fixed therein; a bolt engageable with the tenon of a hasp and 85 freely pierced by said post; a key-operable, segmental tumbler, also freely pierced by said post and rotatable thereon beneath said bolt; means co-acting with said tumbler 90 whereby said bolt is locked against retraction and liberated for retraction, upon said tumbler being duly shifted, accordingly into varying positions in its plane of rotative action; and a bolt-controlling resilient 95 element, the latter serving, indirectly through the medium of said tumbler, to yieldingly hold said bolt protracted.

7. A latch comprising a casing having an upstanding post fixed therein; a bolt engageable with the tenon of a hasp and freely pierced by said post; a key-operable tumbler, also freely pierced by said post and rotatable thereon beneath said bolt; means 100 for yieldingly retarding the tumbler aforesaid in its rotative action; and a bolt-controlling resilient element, the latter serving, indirectly through the medium of said tumbler, to yieldingly hold said bolt protracted.

8. A latch comprising a casing having an upstanding post fixed therein; a bolt engageable with the tenon of a hasp and freely pierced by said post; a key-operable tumbler also freely pierced by said post and 115 rotatable thereon beneath said bolt; an evener coöperating with said bolt, fitted with a boss, and serving to yieldingly retard the tumbler in its rotative action; and a bolt-controlling resilient element, the latter serving, indirectly through the medium of said evener, to yieldingly hold said bolt protracted.

9. A latch comprising a casing having an upstanding post fixed therein; a bolt engageable with the tenon of a hasp, freely pierced by said post, and having a thumb-piece rising therefrom and fitted with a key-hole in its crown; a segmental tumbler, also freely pierced by said post and rotatable 125 130

thereon beneath said bolt, said tumbler having a reduced extension projecting upwardly through the bolt aforesigned, and merged into a key-receiving stem, somewhat upwardly through and beyond which, and into said thumb-piece, projects the post aforesigned; in line with the key-hole there-

above; and a resilient element, the latter serving, indirectly through the medium of said tumbler, to yieldingly hold said bolt 10 protracted.

BRODIE J. RICHARDSON.
CLAIRES BARBER.
